United States Patent Office

Des. 208,061

Patented July 11, 1967

208,061

CLOCK

Harry L. Laylon, Syracuse, N.Y., assignor to Sunbeam Corporation, Chicago, Ill., a corporation of Illinois

Filed July 18, 1966, Ser. No. 3,123

Term of patent 14 years

(Cl. D42—7)

Fig. 1.

Fig. 3.

FIG. 1 is a front elevational view of a clock showing my new design;

FIG. 2 is a top plan view thereof; and

FIG. 3 is a cross-sectional view thereof taken along the line 3—3 of FIG. 1.

The dominant features of the design are shown in full lines.

I claim:

The ornamental design for a clock, as shown and described.
